UNITED STATES PATENT OFFICE.

GUY F. SCOTT, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC SWITCH.

Application filed December 7, 1920. Serial No. 428,862.

My invention relates to switches and particularly to such push-button control switches as are employed to intermittently open and close an electric circuit or to control relays and like apparatus, through an auxiliary circuit.

The object of my invention is to provide a switch of the character described which shall possess the advantages of simplicity, efficiency of operation and cheapness.

Another object is to provide a switch the parts of which shall be readily accessible for replacements and repairs without removing it from its support.

Another object of my invention is to provide a bridging member and a contact tip therefor of such form that the tip may be firmly secured to the bridging member without the employment of any securing means, such as rivets.

Still another object is to provide a switch with a push button that shall have a yielding connection to the bridging member, in order that each of said parts may have a small amount of movement independently of the other.

My invention is illustrated in the accompanying drawings wherein—

Figure 1 is a view, partially in side elevation and partially in section, of one form of switch to which my invention may be applied;

Fig. 2 is a similar view of another form of switch embodying my invention;

Fig. 3 is a sectional detail view of the push-button member of the switch;

Figs. 4 and 5 are plan and longitudinal sectional views, respectively, of a bridging member, and

Fig. 6 is a view, in end elevation, of the switch box.

The switch parts are mounted in a box which is composed of a member comprising a bottom 6 and integral ends 27 and 28 and a member comprising a cover 7 and integral sides 29 and 30. The bottom 6 has upwardly projecting side edges 31 and 32 to prevent spreading of the sides 29 and 30 of the member 7 and also, has a pair of lugs 33 and 34 to which the cover is attached by means of bolts or screws. Openings 8 and 9 are provided in the respective ends of the box.

A switch base 10 is located on the bottom 6 of the box and has a terminal member 11 and a stationary contact member 12 (Fig. 1)

secured thereto. The conductors (not shown), to which the contact members 11 and 12 are connected, may extend through either or both of the openings 8 and 9, in the usual manner, and the circuit may be completed across the contact members by means of a movable contact or bridging member 13 which is mounted on the base 10 and is connected to the terminal member 11.

The bridging member 13 is actuated by a push-button 14, and, in the construction shown in Fig. 1, it is normally out of engagement with the stationary contact member 12. In the construction shown in Fig. 2, the bridging member is normally in engagement with a stationary contact member 15 and, consequently, the circuit is normally closed.

In practice, these switches are usually mounted in pairs, the push button of the switch of Fig. 1 being provided with a colored disk 16 (Fig. 3) and the push button of the switch of Fig. 2 being provided with a disk of a different color. It is customary to provide a white disk for the push button which is used to set the controlled mechanism in motion and to provide a red disk for the push button which is used to bring such mechanism to a stop. However, these are mere details, as either switch may be used alone in a variety of ways, such, for example, as for operating mechanism intermittently or for controlling an auxiliary circuit which actuates a relay to control a main circuit.

As shown in Fig. 3, the push button is made of molded material, such as bakelite, and is provided with a shouldered body portion 17. A recess is formed in the top of the button, in which one of the colored disks above referred to may be secured.

A stem 19 is molded in the body portion 17 and projects through a hole 20 in the bridging member 13. The end of the stem 19 is upset, as indicated at 21, to prevent the withdrawal through the hole 20 but permits relative movement of the stem and the bridging member 13. A compression spring 24 is placed between the push button and the bridging member 13 to take up the lost motion between such members by normally maintaining the push button in its outermost position with respect to the bridging member.

The purpose of the lost-motion connection

just described is to normally maintain the push button in engagement with the under side of the cover plate 7 and thus exclude moisture and dirt from the switch box and 5 provide a reasonable amount of play between the push button and the bridging member, so that, as the bridging member moves up and down, the push button need not follow the arc described by its free end but may 10 move vertically in the opening in the cover member.

In the form shown in Fig. 2, the lost-motion is so arranged that the bridging member 13 will not be held out of engagement 15 with the stationary contact member 15, as would happen if the push button 14 were rigidly secured to the bridging member and the cover plate 7 became dented or otherwise so deformed as to prevent complete outward 20 movement of the push button.

The sides 29 and 30 of the box are formed integrally with the cover, in order that, when the cover is removed, the switch parts may be accessible for repairs and for the connection 25 of wires which may be passed through the holes 8 and 9 of the ends.

It will be observed that the stationary contact members and their terminals are angularly disposed on the base in order that, in 30 case a plurality of boxes are mounted close to one another, the terminal screws may be reached by a screw driver from a point where an adjacent box or the ends 27 and 28 will not interfere.

35 The bridging member 13 is provided with another hole 22 adjacent to its free end, and a tip 23 of soft metal, such as copper, is folded over such end and pressed tightly thereon, as shown in Fig. 5, to cause some of 40 the metal to flow into the opening 22 and maintain the tip 23 securely in position without the necessity of using rivets.

Inasmuch as the bridging member 13 is composed of relatively hard flexible material, such as phosphor bronze, it is desirable 45 to have a contact tip formed on the end thereof of material which is a better conductor.

Utilization of the switches in pairs is not 50 necessary in order to secure the operations accomplished by the devices of Figs. 1 and 2. For example, the bridging member may be utilized to close a circuit at each extremity of its movement.

55 Various other modifications may be made in the construction without departing from the spirit of the invention, as defined in the accompanying claims.

I claim as my invention:—

1. In an electric switch, a switch box, a cover therefor provided with an opening, a push button extending through the opening and having a shouldered portion normally in engagement with the under side of the cover, a bridging member having one end connected to a stationary terminal member and its other end adapted to engage a stationary contact member, a stem extending loosely through the bridging member and having an expanded end to normally abut against the under side of said member and its other end rigidly seated in the push button, and an expanding member lying between the push button and the bridging member for yieldingly holding them in spaced relation. 60

2. In combination, a switch box having a cover provided with an opening, a push button of molded material extending through 70 said opening and having a shoulder to normally engage the under side of the cover, a bridging member having one end connected to a stationary terminal member and the other end adapted to engage a stationary 75 contact member, a stem extending through, and slidably vertically in, the bridging member and having an expanded end to normally engage the under side of the bridging member and having its other end molded in the 80 push button, and means for normally holding the push button in extended position with respect to the bridging member. 85

3. In an electric switch, a stationary contact member, a movable contact member having one end thereof adapted for movement into and out of engagement with the stationary contact member, said movable contact member having a perforation adjacent to said end, and a contact tip folded over the end 95 of the movable contact member and compressed tightly thereon to enter the said perforation. 90

4. In an electric switch, a stationary contact member, a movable contact member mounted for movement into and out of engagement therewith and having a perforation, and a contact tip of relatively soft material folded over the said perforation in such manner that compression thereof will 105 cause metal to flow therefrom into the perforation to form a rivet-like holding member for the tip. 100

In testimony whereof, I have hereunto subscribed my name this 30th day of November 110 1920.

GUY F. SCOTT.
